FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

SPEED-GEAR FOR BORING-MILLS.

1,185,062.

Specification of Letters Patent. Patented May 30, 1916.

Application filed December 3, 1914. Serial No. 875,329.

To all whom it may concern:

Be it known that I, FREDERICK F. CLARKE, citizen of the United States, residing at Franklin, in the county of Venango and State of Pennsylvania, have invented certain new and useful Improvements in Speed-Gears for Boring-Mills, of which the following is a specification.

The object, construction and operation of my improved speed gear for boring mills, are herein set forth with sufficient clearness to enable those skilled in the art of boring mill construction, to make and use the same.

15. The object of this invention is to provide a simple, easily - operated speed - changing mechanism for the driving gear of the table of a vertical boring and turning mill, and to provide said gear with an index system 20 which will inform the operator what to do in order to secure any possible speed change, and will also plainly indicate to him what speed is being employed.

The construction whereby these objects 25 are attained is clearly shown in the drawings, the various figures of which are as follows:

Figure 1 is an elevation of a portion of said gearing, showing the speed-changing 30 devices which coöperate therewith. Fig. 2 is a central horizontal section of the speed-changing mechanism, or manipulating means whereby said changes are effected. Fig. 3 is a front elevation of said manipulating devices, showing especially the index system which is employed in connection therewith. Fig. 4 is an elevation of additional gearing which coöperates with that shown in Fig. 1, and which is partially indicated by dotted lines in said Fig. 1. Figs. 5, 6 and 7 are details of the mechanism shown in Fig. 4. Figs. 8, 9 and 10 are details of the mechanism shown in Fig. 1.

It is believed that the construction and 45 operation of this speed-changing mechanism will be better understood, if a definite line of drive through the various gears is first pointed out, and this I will now proceed to do.

50. The main drive pulley is mounted upon the shaft 2; said drive pulley 1 is the clutch-pulley shown and described in my co-pending application Serial No. 875,322 for a patent for improvements in multiple-disk 55 clutch pulleys, filed at even date herewith.

From said shaft 2, the transmission is through the gears 3, 4 and 5, to the shaft 6, thence through the bevel gears 7 and 8 to the shaft 9, which is shown in dotted lines in Fig. 1. To said shaft 9 is keyed a gear 60 10,—also shown in dotted lines in Fig. 1—that meshes with and drives gear 11 which is revolubly mounted upon the main driving shaft 12 that drives the table 13. Mounted upon and feathered to said shaft 12, is a 65 longitudinally - movable clutch - element 14 which may be placed in engagement with a coöperating clutch-element carried by the gear 11, or a coöperating clutch - element carried by the adjacent end of the gear- 70 sleeve 15, which sleeve is also revolubly mounted upon said shaft 12. When said clutch 14 is in the position shown, (Fig. 1) shaft 12 is directly driven by gear 11, and from said shaft 12 motion is transmitted to 75 table 13 by the bevel gear 13'.

I have now pointed out one line of drive from pulley 1 to table 13 disregarding the speed-changing means which I employ to secure various speeds of said table 13. It 80 is necessary, however, to be able to vary the speed of said table, and it is the construction, combination and operation of the means whereby such variations are accomplished that constitute the invention here 85 set forth, and particularly pointed out and defined in the claims.

The construction of the mechanism for securing changes of speed and the operation of same are as follows: Between the shaft 90 2 and the shaft 6—Fig. 2—is suitably mounted an intermediate shaft 16, to which gear 4 is keyed; also keyed to shaft 16, are the gears 17 and 18. Connected to the gear 3 is a gear 19, which gears 3 and 19 form a 95 unitary structure, which is provided with a flanged hub 20, for the purpose of moving said structure longitudinally upon said shaft 2, to which it is non-revolubly secured by means of a feather which slides in the 100 seat 21. Engaging said hub 20 is a shifting-arm 22 that is connected to the vertical shaft or rod 23 which is actuated by the lever 24. Said lever 24 is connected to the manipulating lever B by means of the reach- 105 rod 25. We will now find it convenient to refer to the element 3—19—20 as the "B element" and this designation will be employed where suitable.

From the foregoing description, it may 110

be readily understood that, by operating lever B, said B element may be shifted so that gear 19 will mesh with gear 18, and this will establish the following line of drive:—
5 through gears 19, 18, 4, 5, which, because of the relative diameters of gears 19 and 18, will be considerably slower than the line of drive through gears 3, 4, 5.

Forming a unitary structure with gear 5
10 is a gear 26, which gears 5—26, for reasons presently apparent, will be termed the "A element." Said A element is longitudinally movable upon its shaft 6, but is made non-revolute thereon through a feather which
15 occupies the seat 27. Engaging said gear 26 is a shifting-arm 28 secured to a vertical rod 29 which is actuated by means of the lever 30 which is connected to the manipulating-lever A by means of a reach-rod 31.
20 By manipulating said lever A, said A element may be shifted so that gear 26 will mesh with gear 17, when a line of drive will be established through gears 3, 4, 17, 26.

From the foregoing description, it may be
25 readily understood that four different speeds of the gears 7 and 8 may be secured by the manipulations of levers A and B.

It should be kept in mind that gear
11—Fig. 1—is driven by a gear 10, previously mentioned, that is secured to the shaft 9 upon which gear 8 is mounted. Now, independently of the speed changes which may be had in the gearing shown in Fig. 4, three additional changes of speed are provided for in the gearing shown in Fig. 1 which additional changes may be secured by shifting the clutch element 14 also by shifting the unitary element composed of gears 32, 33 and collar 34, which element 32—33—34 will be termed the cam-element, and so referred to when it is found desirable to use this term. For the purpose of shifting both said clutch-element and said cam-element, I employ the double-groove cam
40 35, which is clearly illustrated in Figs. 8, 9 and 10. Said clutch is shifted through the medium of the yoke-lever 36, the arm 36' of which is engaged and actuated by the cam-groove 37; said cam-element is shifted
45 by means of the lever 38, the arm 38', of which is engaged and actuated by the cam-groove 39. For the purpose of manually operating said cam 35, I provide the construction shown especially in Fig. 2 and
50 which is further illustrated in Fig. 3, which construction is substantially as follows: For the purpose of revolving said cam, I mount the same upon a hollow shaft 40, to the outer end of which is attached a gear 41. Meshing with said gear 41 is a pinion 42 which is keyed to the arbor 43, and to which arbor is also keyed the driving miter-gear 44 which, in turn, meshes with and is driven by pinion 45 that is manually operated by means
55 of the crank 46. The shaft 46' to which

said crank and said pinion are secured passes revolutely through its bearing which is formed in the plate 49 and gear 48. Also keyed to said shaft 43, is a bevel pinion 47 which meshes with and actuates the index-plate 49 through the medium of gear 48. The ratio of gear 48 to pinion 47 being
70 three-to-one.

Lever 50 does not relate to the speed-changing mechanism but is for the purpose of starting and stopping the machine, also for locking the gears above described and the cylindrical cam in their various adjusted positions, and the operation of said lever and said locking mechanism will be fully
75 described in due order.

With reference to the changes of speed which it is possible to secure in the gearing shown in Fig. 1, they are as follows: As previously stated, sleeve 15 is revolute upon its shaft 12 and is operatively connected thereto by the clutch 14. Gears 51 and 52 are keyed to the sleeve 15; gear 53 is keyed to shaft 54 and the cam-element (32—33—34) is movable longitudinally upon said shaft 54 by means of the lever 38, and is positively driven by said shaft. When clutch member 14, which is positively driven by shaft 12 is in the position shown, shaft 12 is driven directly by gear 11, and gears 32, 51, 52 and 53 are merely idlers; when said clutch is shifted to engage said sleeve 15 the line of drive is through gears 11, 53, 32 and 52. Now, if the clutch remains in engagement with said sleeve, and gear 33 is caused to
80 mesh with gear 51, then the line of drive is through gears 11, 53, 33 and 51.

The three variations of speed just described, multiplied by the four variations of speed previously described, gives a total
105 of twelve variations.

The positions of the levers A and B, also the manipulation of crank 46—as indicated by the index plate 49—necessary to secure said speed changes, will now be pointed out. Upon the escutcheon 49', through which the handles of levers A and B project, are placed the letters "R" and "L," which indicate right and left, respectively, as the operator faces the escutcheon. Also located centrally above the index plate 49 are the letters "A" and "B;" upon said index plate—which is revolute—are located three equally-spaced, radially disposed columns of index; the figures in said columns indicate the number of revolutions per minute which it is possible to obtain, which are, 3, 4, 6, 8; 11, 15, 21, 29; 39, 53, 73 and 100.

Now, inasmuch as the respective positions of levers A and B and the plate 49, as these are shown in Fig. 3, indicate a speed of 100 R. P. M., we will show how this is obtained. The operator of the machine desiring to secure a speed of the table of 100 revolutions per minute, selects the index column on plate
125 130

49 in which is contained said number 100; he then turns crank 46 until said column is vertically-positioned beneath said letters A and B as shown. By referring to line 4 of said index in which the number 100 occurs, it will be noted that the letter R is beneath the letter A upon the escutcheon, which indicates that lever A should be positioned to the right; it will likewise be noted that the letter L on the index is beneath the letter B on the escutcheon, which notes that lever B should be positioned to the left, and this is precisely the arrangement shown in said Fig. 3. With plate 49 remaining in the same position, and both levers positioned to the right, a speed of 73 will be obtained; with both levers to the left a speed of 53, and with lever A to the left and lever B to the right, a speed of thirty-nine R. P. M. of the table will be had.

The primary object of turning crank 46 is to place said cam-element (32-33-34) and the clutch element 14 in their proper positions, but, incidentally, the turning of the index disk 49 informs the operator precisely what to do, and shows him plainly what is necessary to be done in order to secure a desired speed, also what speed is being developed at any time.

30 It is necessary to provide means for locking the speed changing devices in their respective adjusted positions, so that the gears cannot be shifted while the machine is in motion, as this would be liable to cause damage to the gears, and possibly to other parts of the machine.

It is also necessary to provide means for operating the clutch in the main driving pulley 1, to stop and start the machine; in addition to these requirements it is also necessary to provide a brake whereby the momentum of the moving parts may be instantly checked immediately upon the disengagement of said clutch.

45 I accomplish all of the above functions by means of the lever 50 which is secured to shaft 55 that extends through the hollow shaft 40. A partial turn or rotation of said shaft 55 accomplishes all of said functions through the instrumentalities of the following elements: The clutch mechanism within the hub of pulley 1 is engaged and disengaged by a lever 56,—Figs. 1 and 4—that is connected to the outer end of rod 57 that extends through shaft 2 and has communication with the interior of the hub of said pulley 1. Said clutch mechanism is fully shown and described in an application filed at even date herewith Serial No. 875,332 for a patent for multiple disk clutch.

The locking mechanism for the speed-changing devices shown in Fig. 4 is actuated by the knuckle 58, that is also secured to shaft 55. Said locking means comprises the following details, which are shown espe-

cially in Figs. 6 and 7. To the vertical shaft 23 is rigidly secured a collar 59, the periphery of which is supplied with two notches 60 and 61; the vertical shaft 29 is also supplied with a rigidly-attached collar 62, the periphery of which is likewise supplied with notches 63 and 64.

Attached to the knuckle 58 is a longitudinally-movable locking-bolt 65, which is formed upon the end adjacent to collar 62 into a tongue arranged to enter the notches 63 and 64, or either of same which is properly positioned for the reception of said tongue, and thus prevent the rotation of rod 29 and the actuation of lever 30, to shift the gears to which it is operably connected. Said rod 65 is also supplied with a downwardly-extending pin 66, arranged to occupy either of the notches 60 or 61 of said collar 59, and in a like manner as above stated, prevent the actuation of lever 24 and the shifting of the gears to which said lever is operably connected. When lever 50 is actuated to stop the machine, the pins are thereby withdrawn from their locking positions in the collars 59 and 62, and this will permit the shifting of the gears. When lever 50 is actuated to set the machine in operation this also actuates the locking-rod 65 to lock the levers 24 and 30, thus preventing the shifting of said gears while the machine is in motion.

The locking device for the cylindrical cam 35,—see Fig. 9—consists of a locking-bolt 78, mounted adjacent to one end of said cam, which bolt is adapted to move longitudinally. When in the locking position, the inner end of said bolt occupies one of the sockets 79 in the adjacent end of said cam. The outer end or head of said bolt 78 bears against the actuating collar 80, that is secured to the rod 55, which is actuated by said lever 50. A spring 81 surrounds said bolt and bears against the head of same and exerts an outward pressure thereon, which operates to move said bolt outwardly or to hold it in firm contact with the adjacent lateral face of said collar 80; said face is provided with a cam-notch 82, and when rod 55 is actuated to stop the machine, said notch is moved into juxtaposition to the head of said bolt 78, thus permitting the outward movement of same through the actuation of said spring 81, and its withdrawal and disengagement from cam 35, thus permitting the actuation of said cam for the shifting of the gears and the clutch element which are actuated thereby. In this locking device, when lever 50 and rod 55 are actuated to start the machine, the consequent turning of collar 80 thrusts bolt 78 into a socket 79, thus locking said cam in position, and prevents its actuation while the machine is in motion.

The brake referred to, consists of a drum 130

67 which is keyed to the shaft 2. A brake-band 68 passes around said drum. To either end of said band is secured a tension-clip 69 and 70 respectively, the lower one 70 of 5 which bears upon a suitable rigid support 71 carried by the frame of the machine. Passing through said clips is a tension-bolt 72. Positioned between said clips, and surrounding said tension-bolt, is a releasing-spring 73 the normal action of which is to move said clip 69 away from the clip 70, thus releasing the tension of band 68 upon drum 67. The lower end of said bolt 72 is engaged by one end of a brake-lever 74; 10 to the other end of said lever is connected the lower end of a link 75 which, at its upper end is connected to the knuckle 76, that is also attached to said rod 55.

From the foregoing description, it may 20 be readily understood that, when lever 50 is thrown in one direction it causes the disengagement of the clutch-pulley 1, tightens band 68 upon the brake,—thus instantly stopping the machine—releases the locking-rod 25 from its engagement with collars 59 and 62 and also unlocks cam 35, and that a reverse movement of said lever will cause a reverse action of all of said functions, at the same time, setting the machine in motion. 30

I claim the following:

1. A drive for the table of a boring mill, adapted to drive said table at various speeds, comprising a plurality of driving members, 35 a portion of which are shiftable to operably engage other of said members, a plurality of shifter-elements operable to shift said shiftable members, indicative means carried by one of said shifter-elements indicating the obtainable speeds and the 40 various positions of each shifter-element respectively, which will cause any of said speeds.

2. A drive for the table of a boring mill 45 adapted to drive such table at various speeds, said drive comprising gear-members, a portion of which are shiftable to operably engage other of said members, also a clutch-member shiftable to different elements of 50 said gear members, a plurality of elements each operable to shift one of said shiftable elements and one of said elements being also

operably connected to said clutch, and indicative means carried by one of said shifting-elements adapted to indicate the various 55 respective positions of each of said shifting-elements that will cause said various speeds.

3. A drive for the table of a boring mill adapted to drive such table at various speeds, said drive comprising a plurality of 60 gear-members, a portion of which are shiftable to operably engage other portions thereof, also a clutch member operable to engage different members of said gear-members, a plurality of shifting-elements each 65 operable to shift one of said shiftable elements, and one of said elements being also operably connected to said clutch, indicative means carried by one of said shifting-elements adapted to indicate the various 70 respective positions of each of said shifting-elements to obtain said various speeds.

4. A drive for the table of boring mills adapted to drive said table at various speeds and comprising a plurality of driving members, 75 a portion of which are shiftable to operably engage other of said members, a plurality of shifting-elements operable to shift said shiftable members, indicative means carried by one of said shifting-elements adapted to indicate the various 80 respective positions of each of said shifting-elements to obtain said various speeds, a power-receiving and transmitting element, a clutch adapted to operatively connect said 85 last-mentioned element with said driving gear and to disconnect the same therefrom, a clutch-lever positioned in proximity to said shifting-elements operable to engage and disengage said clutch, a lock arranged 90 to simultaneously lock all of said shifting-elements in their respective adjusted positions and to be actuated by said clutch lever, a brake-drum connected to said transmitting element, and engaging means for 95 said brake, adapted to be actuated by said clutch-lever.

In testimony whereof I affix my signature in presence of two witnesses.

FREDERICK F. CLARKE.
